(57) **CLAIM**

The ornamental design for a hat, as shown and described.

DESCRIPTION

FIG. 1 is a front, right and top perspective view of a hat showing my new design;

FIG. 2 is a rear, left and bottom perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a top, right and front perspective view of the hat, shown in condition of use.

The broken line outline of the partial human figure in FIG. 9 assists in illustrating how the claimed design may appear in a position of use and forms no part of the claimed design. The broken lines in the figures illustrate portions of the hat that form no part of the claimed design.
